Filed Nov. 30, 1970, Ser. No. 26,211

Term of patent 14 years

Int. Cl. D6—04

U.S. Cl. D6—149

The figure is a perspective view of a table illustrating my new design. The figure shows the door equipped front of the commode as well as two sides, the three sides not shown being substantially identical to the two sides shown.

I claim:

The ornamental design for a commode, substantially as shown and described.
